UNITED STATES PATENT OFFICE.

CHARLES E. ADAIR, OF COLUMBUS, OHIO, ASSIGNOR TO EVAN J. JONES
AND WILLIAM E. JONES, CONSTITUTING THE FIRM OF EVAN J. JONES
& CO., OF COLUMBUS, OHIO.

CHICKEN-BROODER.

SPECIFICATION forming part of Letters Patent No. 714,654, dated December 2, 1902.

Application filed July 17, 1902. Serial No. 116,002. (No model.)

To all whom it may concern:

Be it known that I, CHARLES E. ADAIR, a citizen of the United States, residing at Columbus, in the county of Franklin and State of Ohio, have invented certain new and useful Improvements in Chicken-Brooders, of which the following is a specification, reference being had therein to the accompanying drawings.

10 This invention relates to brooders in which young chickens hatched out of incubators are kept during the early stages of their growth; and the invention has for its object to provide a brooder or brooder-box which 15 can be warmed by a lamp and kept at an even temperature and which is of such construction as to provide for a proper circulation of warm air therein, so as to insure the requisite ventilation without too much loss 20 of heat.

In the accompanying drawings, Figure 1 is a longitudinal section of my improved chicken-brooder, and Fig. 2 an end view thereof.

The improved brooder comprises a casing 25 A, which may be of any suitable material, but which will preferably be of wood. The casing or box A is divided into upper and lower parts by the floor B, the upper part or chamber D being the brooder-chamber and 30 the lower part being divided into the lamp-chamber C and the air-inlet chamber C'. The heating-lamp E is located in the chamber C beneath a vertical flue or drum F, opening at its top into a horizontal heating-drum 35 G. Secured in the top wall of the heating-drum F is a small pipe g, extending nearly to the bottom of the said drum. Surrounding the vertical heating drum or flue F between the floor B and the drum G is an annular 40 wall H, affording an annular air-space or heating-chamber f between the flue F and the said annular wall H, this annular air-space or chamber communicating with the air-inlet chamber C', which latter is provided 45 with suitable inlet opening or openings c, and the said wall H is provided near its top with suitable egress-openings h, communicating

with the brooder-chamber D. The end walls of the brooder-chamber D are provided near the bottom of said chamber and at points removed from the said heating drum or flue F with egress-openings b, communicating with flues or pipes I at the ends of the brooder-box.

From the above-described construction it 55 will be obvious that the heated air and products of combustion from the lamp E will pass upward through the flue F and strike the top of the heating-drum G and after circulating about said drum will be drawn outward therefrom near the bottom of the chamber thereof through the outlet-pipe g. The air from the inlet-chamber C' will be gently warmed in the annular air-heating chamber f and will pass upward into the brooder-chamber D through the openings h and after circulating through said chamber will be drawn outward from points near the bottom of said chamber through the egress-openings b into the flues I. Owing to this construction, the brooder-chamber may be kept at the desired moderate temperature and will at all times be properly ventilated by the circulation of warm air therethrough, but without unnecessary loss of heat. To keep all parts 75 of the brooder-chamber at the same temperature as nearly as possible, the ceiling of the lamp-chamber C is preferably provided with a non-conducting lining c', of asbestos or other suitable non-combustible or non-inflammable material.

Having thus described my invention, I claim and desire to secure by Letters Patent—

In a brooder; the combination with the casing A, of a brooder-chamber D in the upper part thereof, a lamp-chamber C and an air-inlet chamber C' in the lower part thereof, a vertical flue or vertical drum F above the lamp-chamber, a horizontal heating-drum G 90 into which the said vertical flue or drum opens, and which horizontal heating-drum is provided with an outlet-pipe extending down near to the bottom of the chamber thereof,

the annular wall H surrounding the said vertical drum or flue F, to form the annular heating-chamber f, said wall H being provided near its top with openings h communicating with the said brooder-chamber, and the said brooder-chamber being provided near its bottom, at points removed from the said vertical heating flue or drum, with the egress-

openings b, and exit-flues I into which the said egress-openings b open.

In testimony whereof I affix my signature in presence of two witnesses.

CHARLES E. ADAIR.
